[57] CLAIM

The ornamental design for a set of components for a motor vehicle comprising a pair of fender panels and a spoiler, as shown and described.

DESCRIPTION

FIG. 1 is a side view of a set of components for a motor vehicle comprising a pair of fender panels and a spoiler according to my novel design, it being understood that the opposite side is a mirror image thereof;

FIG. 2 is a rear perspective view thereof;

FIG. 3 is a rear perspective view thereof elevated from that of FIG. 2;

FIG. 4 is a perspective view thereof from the rear and one side; and,

FIG. 5 is an enlarged fragmentary perspective view thereof from the front and one side, it being understood that a view from the opposite side is a mirror image thereof.

The broken line showing of a portion of a motor vehicle in the drawings is for illustrative purposes only and forms no part of the claimed design.
